UNITED STATES PATENT OFFICE.

FRANZ TRINKS, OF BRUNSWICK, GERMANY.

COMPUTING-MACHINE.

1,208,702.

Specification of Letters Patent. Patented Dec. 12, 1916.

Application filed November 5, 1915. Serial No. 59,789.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Computing-Machines, of which the following is a specification.

My invention relates to computing or calculating machines and in particular to calculating machines of the type in which a setting-up wheel having a variable number of teeth actuates an accumulating mechanism which shows the result of each machine operation, as well as a printing device which causes the item set up, to be printed on a sheet of paper or the like. The relative position of the accumulating mechanism and the printing mechanism is such that the setting-up wheel, during its revolution, actuates in consecutive order first the printing device and thereafter the accumulating mechanism.

The object of my invention is to provide 25 means whereby any alteration in the setting of the accumulating mechanism may be prevented when it is desired to print a total.

My invention will be more clearly understood with reference to the drawings in 30 which I have illustrated a machine of the type to which my invention is more particularly applicable.

Figure 1 is a sectional elevation of a machine in which my invention is embodied. 35 Fig. 2 shows, in a plan view, the setting-up wheel and parts of the accumulating mechanism and the printing device, and Fig. 3 is a portion of a machine in which the setting-up wheel is of a different construction.

40 Referring to the drawings, *c* is the setting-up wheel having a variable number of teeth *e*.

h designates the accumulating mechanism which shows the result of each operation.

45 *h* is the printing device by means of which an item set up can be caused to be printed on a sheet of paper. The operative relation is such that if the wheel *c* is rotated in the proper direction, as indicated by the arrow 50 in Fig. 1, the wheel *c* actuates first the printing device *h* and thereafter the accumulator *h*. The teeth *e* are pivotally mounted on the circumference of the wheel *c*, the pivots *l* being disposed radially. Each tooth is 55 formed as an angle piece with a short and a longer leg. Normally, the longer leg of

each tooth is occupying a position in the plane of the wheel, while the shorter leg is then disposed axially.

m are keys arranged in columns. When a key *m* is depressed, its stem or the like member connected to the key, will move into the path of the teeth *e* and will cause a swinging movement of all those teeth which pass the stem or the like member of the depressed key when the wheel *c* is being revolved in the direction of the arrow. Thus, the teeth are turned into the position shown in Fig. 2 with respect to two teeth on the right hand side of the wheel *c*; the longer legs of which project laterally from the wheel. If the revolving movement of the wheel *c* continues, the laterally projecting legs of the turned teeth are carried into the path of the intermediate wheel *i* which actuates the printing device *h*, and in the course of the further revolution into the path of the toothed wheel *n* forming a part of the accumulating mechanism.

Now, my invention relates to a machine 80 of this type and is carried into effect as follows: When it is desired to cause the machine to print the total of the accumulated items, this total must first be set up by means of the teeth *e*, whereupon the operat-

85 ing handle *d* is turned so that the total is also set up in the printing device *h*. How-

ever, on the continuance of the rotation of the operation handle, the accumulating mechanism would also be actuated with the 90 effect that its setting is incorrectly altered.

It is the object of my invention to overcome this drawback. I attain this object by providing means for returning the teeth of 95 the setting-up wheel from their operative position into inoperative position after the same have passed the printing device *h* and before they are able to actuate the accumu-

lating mechanism. The means for obtaining this effect may be variously constructed; a 100 preferred construction is illustrated in the drawing. I have provided a shaft *b* on

which are fixedly mounted arms *a* which by rotation of the shaft *b* can be moved so near the circumference of the setting-up wheel *c* 105

as to project into the path of the projecting legs of the teeth *e*. The wheel *c* revolving, the operative teeth *e* will strike the arms *a* and thereby be swung back into inoperative 110 position. Instead of providing a separate arm *a* for each setting-up wheel *c*, the arms may be united into an axially extending con-

tinuous plate. The shaft *b* is provided with a handle *f* by means of which the shaft can be given a revolving movement.

Means may be provided for retaining the shaft *b* in each of the extreme positions into which the same can be swung by means of the handle *f*. Such means may consist in a spring *r* mounted with one end upon a stationary pin *s* while the other end is provided with a lug *t* which bears against a collar or hub *v* fixedly mounted upon the shaft *b*. The collar or hub *v* has two notches or recesses *u* which correspond to the extreme positions of the shaft *b* and are adapted to engage the lug *t* of the spring *r*.

When it is desired to cause a total to be printed in the machine, it is only necessary that the operator turns the shaft *b* and therewith the arms *a* or an equivalent plate, by means of the handle *f*. On completion of the rotation of the main operating handle, the shaft *b* with its arm *a* may be returned manually in the same manner in which it was swung into operative position. However, this return movement may also be effected automatically and before completion of the rotation of the operating lever, by means of a pin or lug *g* or an equivalent member connected with one of the parts which are revolved through actuation of the operating lever.

The device according to my invention may just as well be applied in connection with setting-up wheels having teeth which are mounted to be swung about a non-radial axis or which are radially shiftable. An example of such a modification is illustrated in Fig. 3. In this construction the setting-up of the teeth is accomplished by means of well known cams *p* which simultaneously lock the teeth in their position in such a manner that the latter cannot be pushed back by any power acting upon the teeth from outside. For that reason the arrangement in this case is such that the arms *a* or an equivalent plate, when swung into operative position, do not act upon the teeth directly to push them back but strike stops *o* provided on the cams *p* and thereby prevent further rotation of the cams with the effect that the teeth are returned into their initial or inoperative position.

It is obvious that my invention is not restricted to the structure shown in the drawings, but that various modifications may be made in the construction and disposition of the parts without involving a departure from the spirit of my invention.

What I claim and desire to secure by Letters Patent of the United States, is:

1. In a computing machine, the combination of an operable element, shiftable numeral-setting members on said element and adapted to be moved into and out of operative position, a printing mechanism to be

actuated by said members, an accumulating mechanism to be actuated by said members, and means for rendering the operative members inoperative after said members have actuated one of said mechanisms.

2. In a computing machine, the combination of an operable setting-up wheel, radially pivoted teeth on said setting-up wheel adapted to be moved into and out of operative position, a printing device, accumulating mechanism, means for rendering said pivotally mounted teeth operative to actuate said printing device and accumulating mechanism, and means for returning said operative teeth into inoperative position after said operative teeth have passed said printing device and before the same have been able to actuate said accumulating mechanism.

3. In a computing machine, the combination of an operable setting-up wheel, shiftable teeth on said setting-up wheel adapted to be moved into and out of operative position, printing and accumulating mechanisms arranged to be actuated in sequence by said teeth, and means for rendering said teeth inoperative after the latter have actuated said printing mechanism.

4. In a computing machine, the combination of an operable setting-up wheel, shiftable teeth on said setting-up wheel adapted to be moved into and out of operative position, printing and accumulating mechanisms arranged to be actuated in sequence by said teeth, a rotatable shaft, a radially projecting member on said shaft and arranged in the path of said teeth to render the latter inoperative after actuating the first of said mechanisms to be actuated, and a handle on said shaft for moving said member into operative position.

5. In a computing machine, the combination of an operable setting-up wheel, shiftable teeth on said setting-up wheel adapted to be moved into and out of operative position, printing and accumulating mechanisms arranged to be actuated in sequence by said teeth, a rotatable shaft, a radially projecting member on said shaft and arranged in the path of said teeth to render the latter inoperative after actuating said printing mechanism, a handle on said shaft adapted to move said member into operative position, and means for automatically moving said member in a position to be ineffective upon said teeth.

6. In a computing machine, the combination of an operable setting-up wheel, shiftable teeth on said setting-up wheel adapted to be moved into and out of operative position, printing and accumulating mechanisms arranged to be actuated in sequence by said teeth, a rotatable shaft, a radially projecting member on said shaft arranged in the path of said teeth to render the latter inop-

erative after actuating the first of said mechanisms to be actuated, a handle on said shaft for moving said member into operative position, and means for retaining said member in its operative and inoperative positions.

7. In a computing machine, the combination of, an operable setting-up wheel, means for revolving said setting-up wheel, teeth mounted on said setting-up wheel and adapted to be moved into and out of operative position, means for rendering one or a plurality of said teeth operative, a printing device adapted to be actuated by any of said teeth rendered operative, accumulating mechanism adapted to be actuated by any of said teeth rendered operative, the consecutive order of said printing device and said accumulating mechanism being such that any of said teeth rendered operative must first actuate said printing device, means for returning to inoperative position any of said teeth rendered operative, whereby said printing device may be actuated while said accumulating mechanism remains unaltered, and means for moving said teeth returning means into operative position and out of operative position.

8. In a computing machine, the combination, of an operable element, shiftable numeral-setting members on said element and adapted to be moved into and out of operative position, a printing device, an accumulating mechanism, means for rendering said members operative to actuate said printing device and said accumulating mechanism, and means situated intermediate the printing device and accumulating mechanism for rendering operatively positioned members inoperative after the latter have actuated the printing device.

9. In a computing machine, the combination of an operable element, shiftable numeral-setting members on said element and

adapted to be moved into and out of operative position, a printing device, an accumulating mechanism, means for rendering said members operative to actuate said printing device and said accumulating mechanism, means situated intermediate the printing device and accumulating mechanism for rendering operatively positioned members inoperative after the latter have actuated the printing device, and means for automatically rendering said last mentioned means ineffective upon the members after the operatively positioned members have been rendered inoperative thereby.

10. In a computing machine, the combination of an operable element, shiftable numeral-setting members on said element and adapted to be moved into and out of operative position, mechanism to be actuated by said members, means for rendering an operative member inoperative after the member has actuated said mechanism, said means being movable into and out of effective position, and means for yieldably locking said last mentioned means in its effective and ineffective positions.

11. In a computing machine, the combination of shiftable numeral-setting members adapted to be moved into and out of operative position, means for supporting and retaining said members in relative position, a plurality of mechanisms arranged to be actuated by said members, and means for rendering operatively positioned members inoperative after the latter have actuated certain of said mechanisms.

In testimony whereof I have hereunto set my hand in presence of two subscribing witnesses.

FRANZ TRINKS.
